UNITED STATES PATENT OFFICE.

GEORGE F. HARRIS, OF NEW YORK, N. Y., ASSIGNOR TO GORDIS DAY HARRIS, OF KEENE, NEW HAMPSHIRE, AND GEORGE EDWIN HARRIS, OF MAHOPAC FALLS, NEW YORK.

APPARATUS FOR LAYING RAILROAD-TRACK.

SPECIFICATION forming part of Letters Patent No. 340,042, dated April 13, 1886.

Application filed January 4, 1884. Serial No. 116,442. (No model.) Patented in Canada April 15, 1881, No. 12,365.

To all whom it may concern:

Be it known that I, GEORGE F. HARRIS, a citizen of the United States, residing at New York, in the county of New York and State of New York, have invented certain new and useful Improvements in Method and Apparatus for Laying Railroad-Tracks, of which the following is a specification, reference being had therein to the accompanying drawings.

10 This invention relates to improvements in a method for delivering at the forward end of a railroad-construction train the ties and rails which are used in laying the track, and also to improvements in the apparatus for carrying out this method or system of delivery, these features pertaining more especially to a construction of the general character shown in my previous Patent No. 229,702, July 6, 1880.

Figure 1 is a side elevation of a portion of the forward car of a construction-train sufficient to illustrate certain parts of the present invention, this figure showing also the extension-frame adapted to be attached to and detached from said forward car, and showing also the supplemental tie-car with its parts in the positions occupied at the time that the load is being automatically delivered therefrom. Fig. 2 is a top plan view of the same devices. Fig. 3 is a side elevation of one of the extension beams or frames detached. Fig. 4 is a rear view of Fig. 1, the upper car being shown in the position occupied by it before dumping, and the platform-car being shown as loaded with a number of rails. Fig. 5 is a top plan of the upper car, the sliding portion being removed. Fig. 6 is a rear elevation of the same. Fig. 7 is a top view of the sliding portion of the upper car. Fig. 8 is a rear end view. Fig. 9 is an elevation of one of the 40 clamping-irons detached, by which the sliding portion of the upper car is guided and held in place. Fig. 10 is a section on the line $z z$ of Fig. 8. Fig. 11 illustrates in perspective the improved support for the detachable rail of the continuous track, which joins together the portions supported permanently on the car. Fig. 12 is a front elevation of one of the trestles which receives the rails immediately after they leave the forward car. Fig. 13 is an end 45 elevation of another trestle. Fig. 14 is a top

plan view of a portion thereof. Fig. 15 shows the shaft or pintle of the horizontal anti-friction rollers on the trestles. Figs. 16, 17, 18, 19, 20, and 21 are detailed views of the various parts.

55 A represents those rails of the permanent track on the ground which have been fastened in place; A³, the ties or sleepers therefor; C C, the wheels on the platform car of the construction-train, resting upon the rails A A; 6c D, the axle, and D' the stringers or sills of the platform-car, and E the floor or deck supported thereon.

F F represent rails permanently secured to the platform or deck E, and L L represent detachable rail-sections adapted to be held in line with the permanent rail-sections F F by an improved device, to be hereinafter described.

65 F' F' represent ties, bars, or sleepers, preferably secured, as shown, to the top of the deck, the object in using them being to give a support to the rails F, and also to provide platforms or standing-places at the sides of the car for the men whenever it is necessary for 70 them to step out of the way of the tie-car, to be described. Those on the forward car of the train also assist in holding the extension-beams in place.

75 I' represents a beam so arranged as to support an extension of the track beyond the front end of the forward car. This beam I' is detachably secured to the car as follows: J' represents a cross-beam situated at a proper height relatively to the top edge of the car, 80 and at or near the front end thereof. The beam I' is rabbeted at i i, the rabbets being adapted to receive the projecting ends h h of the bars H'. At or near the front end of the car the beam I' rests upon the cross-piece J', 85 and it is held from lateral displacement by means of one or more keys, K' K' K', some passing through the projections h h of the bars H' and one through the beam J'.

90 L² represents an inclined detachable brace for increasing the support for the projecting front end of the beam I', this brace bearing against a cross-piece, L', which has a rear brace, L².

95 When it is desired to secure the beam I' in 100

place, it is first lifted up until it rests upon the cross-piece J' , and the rabbets i are fitted to the extensions h , after which the keys K' are driven into place and the brace L' is fastened against the bracket (shown in dotted lines at l , Fig. 1) and against the cross-piece L' .

5 M represents a stop or abutment, situated a suitable distance from the front end of the beam I' , preferably made of a sufficiently strong 10 heavy block of wood, bolted, as at m , to the beam.

15 Upon the rails F and the extension rails F' the tie-car K is adapted to run. This is preferably constructed in the manner shown, and 20 as will be now described.

25 N N' represent the supporting-wheels, which rest upon the track F F' , and which carry a truck-frame, which, for some purposes, may be of any suitable character, but which, for 30 the ends at which I aim, I prefer to construct in the way which will be readily understood by examining Figs. 1, 5, 6, 7, 8, 9, and 10.

35 N' N' represent the side sills of the frame, N^2 the end sills, and N^3 N^3 sills inside of and 40 substantially parallel to those indicated at N' N' . These parts may be made and secured together in any well-known and suitable way.

45 Upon the car-frame thus made is supported the sliding upper part, which consists of side pieces, O O , and end pieces, O' O' . At the front end there is a cross-beam, O^2 , which serves a purpose to be hereinafter set forth. Upon the top of the side pieces, O O , are smooth strips O^3 O^3 , to receive the ties. In the 50 under sides of the side pieces, O , are formed grooves, as shown at o , which, if desired, may be lined or faced with metallic wearing-pieces. By means of these grooves the side pieces are adapted to more or less surround and rest upon 55 anti-friction rollers o' , which are mounted in seats or sockets in the intermediate sills, N^3 , of the car-frame. When the frame O O' is thus mounted, it will be seen that it can readily slide forward and back relatively to the car-frame N N' N^2 below it.

60 In order to hold the two frames in proper positions relatively to each other, and to stop the movement of the sliding frame relative to the lower, I combine with them clamping-irons of the character shown in Figs. 9 and 10, each having a plate, P , by means of which it can be bolted to the outside of one of the sills N^3 , and having an upwardly-projecting plate or arm, P' , which lies by the outer face of 65 one of the side pieces O , and an inwardly-projecting lip or flange, p , which lies above and engages with a bar, o^3 , bolted to the outside of the side sill, O , of the sliding frame. Any suitable projection on the sliding upper portion may be depended upon for stopping it. Thus, the bolt-heads o^4 may be utilized 70 for this purpose—that is to say, so arranged as to strike against the upwardly-projecting plate P' , they being preferably about two feet apart, more or less, as may be found necessary; or these bolt-heads may be countersunk, and stops of other construction and character

75 may be used. The beam O^2 may be so arranged as to strike against the car when the sliding platform returns, and another stop of similar character might be used to limit the 80 forward motion of the platform.

85 The device above described can be used in the following manner for automatically delivering the ties upon the road-bed in large numbers on lines substantially parallel to those in which they lie when in place on the ground: The ties are first taken from the platform of the construction-car and placed upon the upper car, K , they resting upon the ribbon pieces 90 O^3 , and after a suitable number are placed thereon a forward impulse is given to the car, which moves forward on the rails F and F' until the forward wheels strike the stop or abutment M . Thereupon the lower portion 95 of the car stops, but the upper sliding part continues forward for about two (feet more or less) until the weight of the ties bears down the forward end sufficiently to allow them to slide off, which is rapidly effected. The beam O^2 assists in bearing down the forward end of the sliding frame, and also receives the impact when the frame strikes against the projecting ends of the beams I I' . After the last tie has slipped from the sliding platform, the weight 100 of the rear end again brings all of the wheels upon the rails, and the car is ready to be withdrawn for another load.

105 In order to prevent the sliding frame from being jolted or thrust out of place, a lock or catch may be used. Thus, Q Q' represent a bent lever, pivoted at q to the car-frame N N' , and R is a shoulder on the sliding frame, adapted to engage with the shoulder q' . While these two parts are engaging, it is impossible for the truck-frame to slide forward; but when the operator desires such forward sliding he can thrust the bar Q out of engagement. The bar may be held by a spring or pin, or other suitable device.

110 Having thus described the devices by means of which I deliver the ties at the front end of the construction-train, I will now proceed to set forth the means by which I carry the rails to the point where they are to be secured on the ground.

115 In Fig. 4 I have shown how the rails are stored on the car, said storing being accomplished in a way not followed by any one prior to my doing so, as far as I know—that is to say, I arrange the rails in two piles upon each car, one pile being upon each side of the center.

120 T T' represent planks, beams, or heavy boards, secured to the deck of the car between the two piles of loose rails A' , the cross-ties or sleepers H' being preferably arranged with spaces between the inner ends of those which are opposite to each other, in order that the said planks or beams T may be fitted in place. The planks or beams do not extend 125 the full length of the train, but the ends of those on adjacent cars are joined by means of supplemental intermediate short planks or beams, T' . I prefer to have this joining ef-

fected in the manner shown—that is to say, by constructing the ends of the intermediate plank, T' , and of the permanent ones in such way that portions thereof shall always overlap. This can be done as shown—that is, by forming a recess somewhat V-shaped in the end of each permanent plank or beam, and making a convex V-shaped projection on each end of the intermediate plank adapted to fit into the socket on the permanent one; or the parts may be reversed, the permanent one having the convex projection and the detachable one having the concave recess.

t t represent bars or straps of wood or iron secured to the upper surface of the planks or beams T , and $t' t'$ are similar bars or straps fastened to the intermediate detachable plank, T' . These are arranged at a suitable distance apart, leaving a small groove or way between them.

$T^2 T^3$ represent a frame adapted to support one or more of the loose rails A' . This frame has one or more shafts or axles (preferably two) mounted therein, each axle carrying three wheels. Two of these wheels, $t^2 t^3$, are of a similar diameter, somewhat larger than that of the intermediate wheel, t' . The latter wheel is adapted to be situated between the bars $t t$ and $t' t'$, and the said wheels and bars operate to guide the frame $T^2 T^3$. The wheels $t^2 t^3$ rest upon the planks or beams T T' outside of the bars or straps $t t$, and revolve when the frame $T^2 T^3$ is pushed forward or back.

I am aware of the fact that for many years cars (considered broadly) have been used in lumber-mills and other places for the moving of bars and beams from place to place; but I am not aware of the fact that a continuous support for such a car with a substantially unbroken surface has been used with a construction-train of cars, the track extending continuously from one car to the other, and the car being used for transporting the rails along the train.

I am, aware, also of the fact that roller-tramways have been used on the cars of construction-trains for many years, some having the rollers situated by the sides of the cars and some between the sides thereof. In some respects, however, a continuous track is preferable to those roller-tramways, and in doing away with the latter I accomplish several advantages. A roller-tramway suitable for this purpose is much more expensive than are the means which I have herein shown and described.

Upon the forward end of the small car $T^2 T^3$ there is mounted a roller, T^4 , so situated that when the rear end of a rail upon it is being lifted up the forward portion will rest upon the said roller. When the car is at the front end of the train, the operator, after lifting said rear end, can readily slide the rail forward off from the car.

$T^5 T^6$ represent blocks or stops adapted both to prevent the car $T^2 T^3$ from going too far forward and at the same time prevent the

forward end of it from swinging down when the rear ends of the loose rails thereon are being elevated. The forward ends of the side bars, T^2 , of the car can be rabbeted, as shown at f , one wall of the rabbet being adapted to rest upon the block T^5 , and the other wall or shoulder thereof being adapted to abut horizontally against the same; or, instead of two separate blocks, a beam may be fastened across the track from one side to the other.

Having described that form of construction, which at present I prefer to use, I will now say that instead of the parts last above described in detail use may be made of others of a somewhat modified character. Thus ordinary T-shaped rails could be arranged at or near the center of a car between the two piles of loose rails, and upon these a car with flanged wheels could be transported, there being suitable detachable connecting rails between those permanently secured to the cars. Again, use might be made of a plain smooth-surfaced plank in combination with a car having one or more rollers extending from side to side of the plank, and with flanges or suitable guides to hold them properly thereon. However, I do not wish the other features of the present invention to be limited to any special style of devices for carrying forward the rails, as the other objects may be advantageously attained regardless of this portion of the mechanism. As the forward end of the rail which is being advanced leaves the front platform-car, it is received upon a trestle having an anti-friction roller, V . This trestle is preferably constructed in the manner shown—that is to say, with four inclined legs, V' , bottom sills, v' , connecting-pieces v^2 at the front and rear, connecting-pieces v^3 at the sides, a strong heavy bearing-block, v^4 , at the top of each side, and supplemental anti-friction rollers, v^5 . The anti-friction roller V is mounted in the bearing-blocks v^4 , as are also the supplemental rollers v^5 . These latter are preferably mounted upon the devices shown detached in Fig. 15. They consist of a shaft or pintle, v^6 , having a flanged head and a nut, v^8 , which engages with the end of the shaft or pintle v^6 . The shaft passes downward through the bearing-block v^4 , and the nut v^8 bears against the under side thereof. As the rail is moved forward upon the roller V , the supplemental anti-friction rollers insure that there shall be no resistance at the sides of the rail. Of these trestles as many may be used as are found necessary to carry the rails forward to a point where they can be conveniently manipulated. When a series of two or more are employed, they are preferably graduated in size, those farther from the car being lower than those nearer.

I herein describe the extension beams or bars as situated on or nearly on the horizontal plane of the main longitudinal beams or sills of the platform-car, this description where it appears being intended to contradict the particular construction shown from those

mechanisms in which a high overhanging forwardly-projecting frame is used.

Certain advantages are attained by having the forwardly-extending support near the 5 plane of the bed of the car; but there are features of my invention which do not depend upon this exact location.

I believe myself to be the first to have combined with a construction-car and devices for 10 moving endwise of said car the track material, a support extending forward from said car on horizontal lines and having its front end at a distance above the ground, this support being adapted to receive and hold track material 15 preparatory to its being lowered to the ground.

Prior to my invention use had been made of an inclined chute, the rear end of which was supported upon the front end of the construction-car and the forward part of which rested 20 upon a truck. When these inclined chutes have been used, the material, whether rails or ties, must, as soon as it enters them, necessarily pass immediately down to the end, whereas when the forwardly-projecting support lies 25 upon horizontal lines the material can be temporarily retained thereon, if it becomes necessary.

Of course it will be understood that any of the devices known at the date of this patent 30 may be employed to support the track material at points in front of the forward construction-car. For this purpose I at present prefer to use beams like those at I', and to support them as shown, yet there may be more or less 35 modification in this respect, and I also prefer that the guide or track on the forwardly-extending support and on the top of the car should be of the nature of an ordinary tram-track or railroad-track.

40 One part of my invention can be preserved so long as there is such a track or guide upon the forward construction-car to receive a vehicle, and a forwardly-projecting support adapted to hold said vehicle or the material 45 carried thereby.

Prior to the date of this patent use has been 50 made of a support in front of the construction-car, said support consisting of a truck upon wheels at one or both ends, it being adapted to receive the track material, and also adapted 55 to hold and guide a vehicle moving forward from the construction-car, and it will be understood that such devices may be employed in lieu of the support I' shown without departing from the spirit of my invention.

Another feature of said invention can be 60 preserved by employing a series of two or more transportation-cars provided with devices for taking the track material continuously 65 over the series of cars from one to the other, in conjunction with a support projecting forwardly from the front car to receive the material preparatory to its delivery to the ground; and so far as this part of the invention is concerned I do not wish to be limited to having the beams or forwardly-projecting supports located in exactly the horizontal

plane shown, as said support may be considerably higher, or even below the bed of the car, and still permit the accomplishment of 70 the advantages at which I aim, if means be employed for pushing or carrying material above and along the series of cars from one to the other until it reaches said support; nor do I wish to be limited to a construction in 75 which there must necessarily be an immediate or simultaneous delivery of a large number of the ties to the ground, as some of the advantageous features of the construction shown can be preserved without following 80 such a course.

The invention is as applicable to those construction-trains in which all of the cars are utilized in transporting the material from the depots to the points where the track-laying 85 is taking place, as it is in those trains having specially constructed cars at the forward end, which cars are generally left standing at the point of construction, and are not used for purposes of transportation. Sometimes these 90 latter cars are provided with derricks and other implements, and they can be used as well in carrying out my system as can the ordinary platform-cars.

When a tie-car above the construction-cars 95 is used, it is not necessary that the front support should be exactly horizontal, though it is preferable that it should be so.

In Fig. 11 I have shown one of the improved supports which can be employed for 100 holding in proper place an intermediate detachable section of rail. W represents the shank or stem, having an eye, W', which can be fastened to one of the rails by a bolt passing between the tread and the flange of the rail 105 through one of the fish-plate holes ordinarily made. The shank W projects forwardly to a suitable distance beyond the rail F, and is then curved outwardly and downwardly, as at w, then inwardly, as at w', to provide a portion 110 to lie below the intermediate rail-section, and then upwardly, as at w''. A support of this kind can be attached and detached with but little trouble, and the intermediate rail-section can be quickly put into place or removed 115 therefrom, and I avoid the necessity of the endwise movements when other supports are employed.

I am aware of the fact that chutes have been 120 used with construction-cars for the purpose of lowering the ties and rails; but I prefer to dispense with chutes and carry the ties on the extension-beams on lines substantially horizontal, and carry the rails on trestles independent of each other and of the car.

125 By having the trestles and the rollers, instead of the chutes heretofore used, I can readily move a rail backward after it has come down to the lowest roller without the necessity of lifting it or moving it laterally by reversing its motion on its roller, and there is no necessity to lift it over or off from the support, as is the case when chutes are used. Half of the rails have to be carried backward

and half forward, and my devices for supporting the rails enable me to carry with great convenience those which are to be moved backward.

5. What I claim is—

1. The herein-described method of transporting by and delivering from a construction-train of cars the material for a permanent track, it consisting in placing the loose ties upon the rear cars of the train and the loose rails upon the forward cars, the latter being arranged in two piles on each rail-car, then carrying over the loose rails on the train and delivering to the ground in front a large number of ties simultaneously, and transporting the loose rails to the front of the train on lines between the two aforesaid piles of rails which are on each car, substantially as set forth.

2. The combination of the platform-car and extension beams or bars situated on or near the horizontal planes of the main longitudinal beams or sills of the platform-car, substantially as set forth.

3. The combination, with a platform car, of extension beams or bars running forward from the car and secured thereto, and a tie-carrier supported upon said beams or bars and adapted to carry material thereon to points ahead of the car, substantially as described.

30. 4. The combination of the platform-car, extension beams or bars situated on or near the horizontal plane of the main longitudinal beams or sills of the platform-car, a track supported upon said beams, and a car whose wheels are fitted to said track, substantially as set forth.

5. The combination, with the forward car of a construction-train, of detachable extension-beams extending forward from said car substantially horizontally, to support a tie-carrier, devices, substantially as described, for clamping said beams to the car rigidly, and a supplemental tie-carrying car adapted to be supported and to run upon the said extension-beams, substantially as described.

45. 6. The combination, with the construction-car, of the detachable extension-beams, which provide a track for an upper supplemental car, and detachable braces, as at L³, for supporting the forward parts of the said extension-beams, substantially as described.

7. The combination, with the detachable extension-beams, of stops or abutments M, secured thereto, substantially as and for the purposes set forth.

8. The combination, with the forward car of a construction-train, of detachable extension-beams beveled or rounded at their forward ends, whereby they are adapted to receive the impact of a tie-carrier at points below their upper edges, substantially as shown and described.

9. The combination, with a construction-car, of a car adapted to move thereon and provided with two frames, one of which is movable relatively to the other, whereby the un-

loading of the material from the car can be facilitated, substantially as set forth.

10. The combination of the construction-car, and the tie-car moving thereon, made in two parts permanently connected together, but of which one is adapted to move relatively to the other, substantially as set forth.

11. In an apparatus for delivering track material to the ground from a construction-train, the combination of a car adapted to be moved upon the car which carries the construction material and a stop or abutment which stops the forward movement of the car at the point where the unloading of the latter is to be effected, substantially as set forth.

12. In an apparatus for delivering track material from a construction-car, the combination, with said car, of a carriage adapted to move thereon and provided with a frame for supporting the material, which frame can swing upward, and a stop arranged substantially as described, whereby the motion of the carriage is arrested, substantially as set forth.

13. In a device for transporting ties from one part of a construction-train to another, the combination of a main frame, as at N' N', a sliding frame thereon, the plate P', secured to one of said frames and having the engaging portion p, wherewith it engages with the other frame, substantially as set forth.

14. In a device for transporting ties from one part of a construction-car to the other, the combination of the movable main frame, a frame connected thereto which can slide relatively, the anti-friction rollers o', interposed between the frames, and connecting devices which prevent a vertical displacement of the sliding frame, but arranged, substantially as set forth, to permit it to move longitudinally, as described.

15. The combination of the main frame N', the sliding frame O O', a connecting-plate, P P', and stops o' to limit the movements of the sliding frame, substantially as set forth.

16. The combination, with a construction-car for transporting track material, of a series of two or more independent trestles (in contradistinction from a chute) in front of the construction-car, each being provided with independent rollers adapted to be arranged in gradually lower planes.

17. In a track-laying apparatus, the combination of the following elements, namely: a series of transporting-cars, an anti-friction guide or track for the loose metal rails extending from one to another of said cars and arranged centrally longitudinally of the train, an apparatus for delivering said rails, consisting of a series of rollers directly in front of the central part of the train, and a supplemental car moving centrally of the train and over the aforesaid guide for the metal rails, substantially as set forth.

18. In a track-laying apparatus, the combination of a construction-car, a track upon said car, a supplemental track in front of said car,

substantially coinciding with the track on the construction-car, and a support, which holds said supplemental track in an elevated position above the ground, substantially as set forth.

19. The combination of a construction-car, a track upon said car, a supplemental track in front of said car and substantially coinciding with the track thereon, a tie-carrying car adapted to move on said track, and anti-friction rollers in front of the construction-car, to support the metal rails as they descend, substantially as set forth.

20. The anti-friction rail-guide having the horizontal roller and the vertical rollers, the latter being arranged immediately above the horizontal roller, substantially as set forth.

21. In a track-laying apparatus, the combination, with a construction-car, of a support in front of said car for track material preparatory to its being lowered to the ground, that part of said support over which the material is transported being substantially horizontal and the rear end thereof being detachably connected with the construction-car, substantially as set forth.

22. The combination, with the train of two or more cars, of a continuous track above and upon said cars, adapted to guide a supplemental vehicle, and a support in front of the forward car adapted to hold track material preparatory to its being lowered to the ground, substantially as set forth.

23. The combination, with the train of two or more cars, of a supplemental vehicle adapted to move above and longitudinally over said cars, means at the ends of the cars to support said vehicle while passing from one to the

other, and a support in front of the forward car to hold the material brought forward by the said vehicle, substantially as set forth.

24. The combination, with a construction-car, of a supplemental car for transporting iron rails over the construction-car, said supplemental car having supporting-wheels, which rest upon the construction-car, and having a downward-projecting guide, the construction-car having a corresponding way for said guide, substantially as set forth.

25. The combination, with a construction-car, of a supplemental car for transporting iron rails over the construction-car, said supplemental car having wheels or rollers, which rest upon the construction-car, and a guide which engages with a way on the construction-car, and an anti-friction roller on the supplemental car adapted to support the rails when they are being pushed forward and off from the supplemental car, substantially as set forth.

26. The combination, with a construction-car having track-rails secured thereto and the intermediate removable rail-sections, of the supporting-bars for the said intermediate rail-sections secured to the rails on the construction-car, and each constructed, substantially as set forth, to have an arm situated below and across an intermediate detachable rail-section, whereby the latter can rest upon and be held by said supporting-bar, as described.

In testimony whereof I affix my signature in presence of two witnesses.

GEORGE F. HARRIS.
